HEADLIGHT BEZEL FOR AUTOMOBILES OR THE LIKE

George W. Walker, Bloomfield Hills, Mich., assignor to
Ford Motor Company, Dearborn, Mich., a corporation
of Delaware

Filed Oct. 3, 1960, Ser. No. 62,343

Term of patent 7 years

(Cl. D48—32)

FIG. 3 FIG. 4 FIG. 5

Fig. 1 is a front elevational view of a headlight bezel for automobiles or the like showing my new design;

Fig. 2 is a side elevational view of the right side of the headlamp bezel as viewed in Fig. 1;

Fig. 3 is a side elevational view of the left side of the headlamp bezel as viewed in Fig. 1;

Fig. 4 is a sectional view taken on the line 4-4 of Fig. 1;

Figs. 5 and 6 are enlarged partial sectional views taken on the lines 5-5 and 6-6, respectively, of Fig. 1;

Fig. 7 is a plan view of Fig. 1;

Fig. 8 is a sectional view taken on the line 8-8 of Fig. 1; and

Figs. 9 and 10 are enlarged partial sectional views

taken on the lines 9-9 and 10-10, respectively, of Fig. 1.

I claim:

The ornamental design for a headlight bezel for automobiles or the like, as shown.
